CONTROL SYSTEM.

Application filed April 12, 1921. Serial No. 460,844.

My invention relates to motor-control systems and it has particular relation to such systems of control as are employed with elevators, dumb-waiters and the like.

- 5 The object of my invention is to provide a system of control whereby an elevator may be automatically dispatched to any desired landing or floor and in which no regular operator is required.
- 10 Systems of such character have come into general use, but, in the main, are perhaps unnecessarily complicated.

I propose to provide a standard elevator hoisting mechanism with a suitable reversing controller operated by means of push-button switches located as desired or convenient. A plurality of selector switches are located, one at each landing, and arranged for operation by the movement of the elevator car. Relays coact with the push-button switches and selector switches to control the movement of the elevator whereby it may be called to any desired landing and dispatched therefrom to any other landing.

- 25 I have shown a single figure which represents, diagrammatically, circuits and apparatus embodying my invention.

A motor, having an armature 1 and a shunt field 1a, is connected to line conductors 2 and 3 by means of reversing contactors 4 and 5. An accelerating resistor 6 is controlled by a contactor 7, and a dynamic-braking resistor 8 is controlled, in the usual manner, by the reversing contactors. An electro-mechanical brake 9 is provided to hold the elevator car at any desired point in its travel. The operation of this brake is controlled by means of a relay 11.

- Relays 12 and 13, together with reversing contactors 4 and 5, are responsive to the operation of push-button switches of a plurality of similar groups 14. Selector switches 15, 16, 17 and 18 are actuated by the cam 19 attached to the elevator car 21. Door switches 22, 23, 24 and 25 control the movements of the elevator in a well known manner; the elevator is inoperative when any door switch is open.

Assuming the elevator car is at the third floor, corresponding to the location of selector switch 17 and door switch 24, if it is desired to dispatch the elevator to the first

floor, push-button switch 26 is depressed momentarily, establishing a circuit for the coil 27 of contactor 5, extending from line conductor 2 through conductors 28 and 29, back contact 31 of relay 11, conductors 32 and 33, push-button switch 26, conductors 34 and 35, selector switch 15, conductor 36, coil 27, conductor 37 and door switches 25, 24, 23 and 22 to line conductor 3. The closure of contactor 5 establishes a circuit for the operating coil 38 of relay 11 extending from line conductor 2 through conductor 39, contactor 5, conductor 41, holding coil 42, braking contactor 43, a section of resistor 8, conductor 44 and coil 38 to line conductor 3.

The closure of relay 11 interrupts a circuit through the push-button switches 70 through the back contact 31. A holding circuit has previously been established for the coil 27 of contactor 5, extending from line conductor 2 through conductor 39, contactor 5, conductor 41, coil 42, contact 43, resistor 75 8, conductor 44, back contacts 45 and 46 of relays 13 and 12, resistor 47, conductors 34 and 35, selector switch 15, conductor 36, coil 27, conductor 37 and door switches 25, 24, 23 and 22 to line conductor 3.

The elevator is directed to the first floor and, in passing the second floor, may actuate selector switch 16. It will be noted, however, that the circuits previously traced do not comprise selector switch 16. Therefore, the elevator continues to operate until the selector switch 15 is actuated, interrupting the holding circuit previously traced, comprising coil 27 and contactor 5. The elevator is, therefore, quickly brought 90 to rest in the usual manner.

Assuming it was desired to dispatch the elevator to the second floor from the third, instead of to the first, as described, it is necessary to momentarily depress push-button 48, establishing a circuit for coil 49 of relay 12 and coil 27 of contactor 5, extending from line conductor 2 through conductors 28 and 29, contact 31, conductors 32, 33 and 50, push-button switch 48, conductor 51, coil 49, conductor 52, selector switch 16, conductor 53, selector switch 15, conductor 36, coil 27, conductor 37 and door switches 25, 24, 23 and 22 to line conductor 100.

3. A holding circuit for contactor 5 and relay 12 is established, extending from line conductor 2 through conductor 39, contactor 5, conductor 41, coil 42, contact 43, resistor 8, conductor 44, contact 45, relay 12, coil 49, conductor 52, selector switch 16, conductor 53, selector switch 15, conductor 36, coil 27, conductor 37 and door switches 25, 24, 23 and 22 to line conductor 3. Relay 11 interrupts the initial operating circuit through all of the push-button switches, as previously described.

The elevator car 21 is directed to the second floor and is stopped at that floor by the actuation of selector switch 16, which interrupts the circuit previously described for relay 12 and contactor 5. While relay 12 is closed, a circuit for serving the first floor is interrupted through back contact 46, which circuit comprises resistor 47, selector switch 15 and operating coil 27 of contactor 5. It is also assumed that door switch 23 is opened automatically, in any well known manner, by the elevator car 21 or by a passenger in the car, so that, while the door at the second landing is open, the elevator cannot be dispatched to or called from any other landing.

If it is desired to dispatch the elevator car to the fourth landing, circuits are established comprising an operating circuit for the coil 55 of the contactor 4, extending from line conductor 2 through conductors 28 and 29, contact 31, conductors 32 and 33, push-button switch 56, conductor 57, selector switch 18, conductor 58, coil 55, conductor 37 and door switches 25, 24, 23 and 22 to line conductor 3. A holding circuit for the coil 55 is established, extending from line conductor 2 through contactor 4, conductor 59, coil 61, back contact 62, resistor 8, conductor 44, contacts 45 and 46, resistor 63, conductor 57, selector switch 18, conductor 58, coil 55, conductor 37 and door switches 25, 24, 23 and 22 to line conductor 3. The operation of the elevator in its upward movement to the fourth floor is similar to that described in its movement to the first floor.

It should be noted that resistors 47 and 63 are of such value as to prevent accidental operation of contactors 4 and 5 by limiting the current to a value below the value necessary to operate these contactors, while permitting sufficient current to flow to maintain these contactors closed after they have been operated in the proper manner. Also, relay 13 functions with respect to selector switch 17 in a manner similar to that in which relay 12 and selector switch 16 coact. When relay 13 has functioned to serve the third floor, all other operating circuits are interrupted by the opening of back contact 45.

Any number of floors may be served by the addition of a corresponding number of selector switches, push-button switches, door

switches and relays corresponding in operation to relay 12. If desired, a group of push-button switches may be located at each floor, as is convenient for the control of a dumb-waiter, since it is not designed to carry passengers. In elevator service one group is located within the elevator car under control of the passengers and other buttons are distributed, one at each of the corresponding floors, to call the car to that floor, after which the car is dispatched to any desired floor by means of the buttons located in the car.

In systems commonly employed, a selector device is connected to the elevator mechanism by means of a chain or gearing. With this arrangement, it is necessary to readjust the selector device from time to time on account of stretching of the elevator hoisting cables, which eventually take a permanent "set." The point at which the elevator stops and the relation of the landing level and car floor level also varies in accordance with the load in the car on account of the elasticity of the hoisting cables. In the present system, this difficulty is overcome by locating the selector switches at the floors where they are actuated directly by the elevator car.

The selector switch mechanism employed in this system is very simple in form, inexpensive in construction and requires a minimum of attention for maintenance. The common type of hatchway limit switch may be employed.

I have shown a simple form of operative control system which is capable of modification to suit particular needs without departing from the essential features and scope of my invention.

I claim as my invention:—

1. The combination with an elevator and a hoisting motor, of reversing contactors therefor, controlling means comprising a plurality of push-button switches and selector switches, a brake for the motor, a relay responsive to the operation of one of said reversing contactors in response to the operation of one of said push button switches for controlling said brake, and a switch actuated by the brake relay for rendering all the other of said push buttons ineffective.

2. The combination with an elevator and a hoisting motor therefor, of a pair of contactors for reversing the motor, a holding circuit for said contactors a plurality of selector switches actuated by the elevator and a plurality of push-button switches for actuating said contactors and for dispatching the elevator to either of two predetermined landings, selectively, a relay responsive to one only of said push-button switches, a selector switch coacting therewith for dispatching said elevator to a predetermined intermediate landing, and means comprising

said relay for interrupting the holding circuit for said reversing contactors comprising said reversing contactors and a pair of said selector switches.

5 3. The combination with an elevator and a hoisting motor therefor, of a pair of contactors for reversing the motor, a plurality of selector switches operated by the elevator, a plurality of push-button switches 10 for actuating said contactors, electroresponsive means comprising only said contactors and a pair of said selector switches for determining the limits of travel of said elevator, and a relay responsive to the operation of another of said selector switches 15 and to said push-button switches for accomplishing an intermediate predetermined stop for the elevator.

4. The combination with an elevator and a hoisting motor therefor, of a pair of reversing contactors having dynamic braking contactors attached thereto, a plurality of push-button switches for effecting the actuation of said reversing contactors, a holding circuit for the operating coil of one of 20 said reversing contactors, comprising the braking contactor of the other of said reversing contactors, and a plurality of selector switches actuated by said elevator for interrupting said holding circuit when said 25 elevator occupies a predetermined position.

In testimony whereof, I have hereunto subscribed my name this 28th day of March, 1921.

EDGAR M. BOUTON.
